LAMP SHADE

Rudolph A. Bushcott, Fort Atkinson, Wis., assignor to Thomas Industries Inc., Louisville, Ky., a corporation of Delaware

Filed Sept. 4, 1963, Ser. No. 76,470

Term of patent 14 years

(Cl. D48—16)

larged scale, taken substantially along the line 10—10 in FIGURE 8, looking in the direction indicated by the arrows.

It is to be understood that the partially shown pattern on the side of the shades in the drawings continues uniformly throughout the broken line area thereof.

I claim:

The ornamental design for a lamp shade, substantially as shown and described.
